HOOK ATTACHMENT FOR LADDERS

John J. McCoy, 1606 Wakefield Ave.,
Youngstown, Ohio 44514

Filed Oct. 31, 1973, Ser. No. 411,346

Term of patent 3½ years

Int. Cl. D8—08

U.S. Cl. D8—246

FIG. 1

FIG. 2

FIG. 3

FIG. 4

FIG. 1 is a perspective view of a hook attachment for ladders showing my new design, and

FIG. 2 is a rear elevational view thereof, and

FIG. 3 is a side elevational view thereof, and

FIG. 4 is a front elevational view thereof.

I claim:

The ornamental design for a hook attachment for ladders, as shown and described.
